UNITED STATES PATENT OFFICE.

LANSING ONDERDONK, OF NEW YORK, N. Y., ASSIGNOR TO UNION SPECIAL SEWING MACHINE CO., OF CHICAGO, ILLINOIS, A CORPORATION OF ILLINOIS.

BLINDSTITCH-MACHINE.

1,070,353.

Specification of Letters Patent. Patented Aug. 12, 1913.

Application filed December 31, 1901. Serial No. 87,960.

To all whom it may concern:

Be it known that I, LANSING ONDERDONK, a citizen of the United States, residing at New York, in the county of New York, State 5 of New York, have invented certain new and useful Improvements in Blindstitch-Machines, of which the following is a description, reference being had to the accompanying drawing, and to the letters and figures 10 of reference marked thereon.

My invention relates to an improvement in sewing machines, and particularly to sewing machines of the blind stitch type, employing a circular looper mounted to travel 15 above the bed plate of the machine, cooperating with a needle which reciprocates back and forth across the line of feed, passing its thread through the material which is crimped over the throat plate. Such a type 20 of machine is shown generally in my prior patent No. 720,732, granted February 17th, 1903; but the object of the present invention is to provide a looper thread retainer or controller, coöperating with a looper which 25 may travel in a horizontal plane above the needle, to take the looper thread and carry it below the path of the needle, so that the needle in its next movement to pass into the goods, will engage the looper thread in its 30 operation of forming an overcast stitch.

By this improvement, an up and down, or inclined movement of the looper to cause it to take the needle loop above the needle, and then carry its own loop to a point below the 35 needle on the other side the line of the seam, may be dispensed with, and the looper be made to move in a horizontal plane, the looper thread spreader, retainer or plunger, acting as above set forth.

40 The invention consists in the various features hereinafter described and referred to in the appended claims.

The invention is illustrated in the accompanying drawings, in which—

45 Figure 1 is a front elevation of a blind stitch sewing machine embodying my invention; Fig. 2 is an end view; Figs. 3 and 4 represent detail plan views of the manner 50 of forming the stitch, the coöperating stitch-forming elements being shown in different positions; and Figs. 5 and 6 represent front and side views, respectively, of a modification of the mechanism for operating the looper thread spreader or retainer.

55 In these drawings, referring to Figs. 1 and

2, 1 represents the standard, 2, the goose-neck, and 3 the depressible work support of the machine, the latter having a cloth plate 4, formed with a V-shaped ridge, over which the material to be sewed is crimped. 60 The feeding mechanism is of the usual type as shown in Fig. 2 and consists of a feed dog which is moved back and forth to feed the material, and up and down so as to be brought into and out of contact with the 65 material. The crimping member is carried by the work support, which is normally stationary and therefore, said crimping member is normally stationary relative to the feeding movement of the feed dog. The 70 looper 5 is secured upon a vertical bar 6, mounted in bearings in the head of the machine, the looper oscillating upon its vertical axis in a horizontal plane, the bar 6 being oscillated by crank and pitman connections 75 7, 8, from the belt wheel 9 of the machine.

The needle 10 is curved as shown, and mounted upon the lower end of a swinging arm 11, the upper end of which is driven by pitman and eccentric connections from 80 the driving shaft A. This needle reciprocates back and forth through the goods, across the line of feed in the manner illustrated in connection with the above mentioned patent.

85 B represents a curved lever pivoted on a stud 12, secured in a lug 13 on the machine frame. It is operated from an eccentric on the main shaft through a pitman connection 14. At the lower end of this lever is secured a rod or plunger 15, which is of shape 90 at its lower end to engage the looper thread. By reason of the curved shape of the lever B, this part 15 travels in the arc of a circle from a point above the needle to a point 95 below it, in a single plane, and is so timed that when the looper commences to recede from its extreme point of movement beyond the path of the needle, the retainer 15 moving toward the low point will engage the 100 looper thread, and as its movement continues will carry the looper thread below the path of the needle, so that the needle will pass above it, and thus secure the looper thread in position necessary in forming the 105 overcast stitch.

The relation of the parts in forming the stitch is shown in Figs. 3, and 4; in the former the looper is shown at the extreme point beyond the path of the needle, and 110

illustrates also that the looper thread, from the eye of the looper, to the point where it is tied up in a stitch in the seam, is beyond the path traveled by the spreader or retainer 15. It will be noticed also from this figure that, it is when the lower end of spreader 15 is above the path of the looper thread that the looper carries its thread beyond the path of said spreader. As shown in Fig. 4, however, when the looper begins to recede from its extreme point the spreader moves forward and swings downwardly to engage the looper thread and carry it into position to be engaged by the needle. It will be seen, therefore, that the operation of the spreader is such as not to interfere with the looper thread other than at the desired time, and that when the spreader has moved back a certain distance from the position shown in Figs. 1 and 4, it will shed the looper thread, so that it can be drawn up into the stitch properly by the action of the looper, and looper thread take up 16.

In Figs. 5 and 6, another mechanism for operating the looper thread retainer or spreader is shown, Fig. 5 being a front view and Fig. 6 a side view, illustrating the same. The bar B' carrying the spreader 15, is driven by a crank B², secured to the head of the machine by a stud through a hole in the head of the machine. B³ is a free turning bearing for the spreader bar B², the latter being free also to slide up and down in its bearing B³. The latter is secured to the head of the machine through the lug B⁴, in which it has a bearing free to turn, so as to conform to the action of the spreader bar B', the part B⁵ of the bearing B³, having a turning fit in the lug B⁴, so when the spreader bar receives its swinging movement by the action of the crank B², which is connected to an eccentric on the driving shaft through ball and stud and pitman connections, as the crank B² swings on its stud, the bar B' being free to slide up and down in its bearing B³, and the latter being free to turn in its bearing, each end of the bar B² describes the arc of a circle, as shown in the dotted line in Fig. 5, which line of movement is on a shorter radius than described by the spreader in Fig. 1, and, therefore, will release the looper thread somewhat more freely than in the other construction.

Various minor modifications and changes may be made without departing from the spirit of my invention.

Having thus described my invention, what I claim as new, and desire to secure by Letters Patent, is:—

1. A blind stitch sewing machine, comprising an overhanging arm, a depressible work support beneath the same, a crimping member carried by said work support, a feeding device operating upon each side of said crimping member, said crimping mem-

ber being immovable in the line of feed, a curved needle supported by the overhanging arm above the work support, means for operating the same to reciprocate the needle back and forth across the line of feed, a thread-carrying implement co-operating with said needle and supported by the overhanging arm, said thread-carrying implement moving in substantially a horizontal plane, and a thread-manipulating device arranged to engage the loop of thread carried by the thread-carrying implement and carry the same into position for the needle to enter said loop. 75

2. A blind stitch sewing machine, comprising a supporting standard, an overhanging arm carried thereby, a cylindrical work support carried by said standard and projecting therefrom, a crimping member carried by said work support, a feeding device mounted within said work support and operating upon each side of the crimping member, said crimping member being normally stationary relative to the feeding movement of the feeding device, a curved needle supported by the overhanging arm above the work support, means for operating the same, a thread-carrying implement co-operating with said needle and supported by the overhanging arm, said thread-carrying implement moving in substantially a horizontal plane, and a thread manipulating device arranged to enter the loop of thread carried by the thread-carrying implement, and carry the same into position for the needle to enter said loop. 90

3. In a blind stitch sewing machine, in combination with a normally stationary work support, a feeding mechanism carried thereby, said work support having means thereon for crimping the work, an overhanging arm, a curved needle reciprocating back and forth across the line of feed above the cloth plate, a thread-carrying looper oscillating in a single plane above the needle, from a point at one side the line of feed where it engages the needle thread, to a point at the opposite side of said line of feed, and a looper thread-engaging device with means for moving it in a single plane from a point above the needle to a point below it on the opposite side the line of seam from that in which the looper engages the needle thread to cause it to engage the looper thread and carry it into position, so that the needle in its forward movement will pass through the looper loop, said needle and looper and looper thread-engaging device being supported by the overhanging arm above the work support. 105

4. In a blind stitch sewing machine, a needle, an overhanging arm, a normally stationary depressible work support, a crimping member carried by said work support and arranged in a plane above said 110

work support and in a plane below said needle, said needle being supported by the overhanging arm above the work support, means for operating the needle across the 5 apex of the crimping member, a coöperating loop taking device also mounted above said work support and a thread manipulating device mounted and operating wholly above said work support and having a movement 10 to position a loop of thread for entrance by the needle.

5. In a blind stitch sewing machine, a needle, an overhanging arm, a normally stationary depressible work support, a 15 crimping member carried by said work support and arranged in a plane above said work support and in a plane below said needle, said needle being supported by the overhanging arm above the work support, 20 means for operating the needle across the apex of the crimping device, a coöperating loop taking device also mounted above said work support and a thread manipulating device mounted and operating wholly above 25 said work support and having a movement to position a loop of thread for entrance by the needle, said manipulating device holding said loop while the needle is in its retracted position.

30 6. In a sewing machine, a needle with

means for reciprocating it back and forth across the line of feed, a looper with means for reciprocating it back and forth across the line of feed, a rocking bearing on the machine frame, a rod or bar freely supported in said bearing, a crank upon the upper end of said rod or bar, and connections between the same and the driving shaft, and a spreader or retainer for the looper thread carried by said bar or rod; 35 substantially as described.

7. In a sewing machine, a needle with means for reciprocating it back and forth across the line of feed, a looper with means for reciprocating it back and forth across 45 the line of feed, a bearing pivoted on the machine frame, a rod or bar having vertical movement therein, a crank pivoted on the machine frame, to which the upper end of said rod or bar is pivotally attached, and 50 means for oscillating said crank, and a spreader or retainer for the looper thread carried by said rod or bar; substantially as described.

In testimony whereof I affix my signature, 55
in presence of two witnesses.
